(57) **CLAIM**

The ornamental design for a pediatric mode key for defibrillator, as shown and described.

DESCRIPTION

FIG. 1 is a perspective view showing our design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The dash-dot-dash broken lines represent the bounds of the claim while the dashed broken lines illustrate portions of the pediatric mode key for defibrillator that along with the broken-line boundaries, form no part of the claimed design.
